UNITED STATES PATENT OFFICE

WALLACE I. STIMPSON, OF HOPEDALE, MASSACHUSETTS, ASSIGNOR TO DRAPER CORPORATION, OF HOPEDALE, MASSACHUSETTS, A CORPORATION OF MAINE

BOBBIN-CLUTCHING MEANS FOR ROTATABLE SPINDLES

Application filed July 23, 1929. Serial No. 380,356.

This invention relates to that type of spindle employed in spinning frames and similar machines in which bobbin clutching members are provided surrounding the spindle blade and fitting within the base of the bobbin to come into clutching engagement therewith and maintain the bobbin in position during the spinning or other operation. Such devices are required to function with great accuracy and are subject to very trying conditions when in use. The spindle is driven at a high speed of rotation and unless the bobbin is accurately centered and maintained concentric with the blade when rotating at high speed, radial vibration takes place, which is not only injurious to the spindle construction but interferes with the spinning or other operation being performed upon the yarn. Even very slight eccentricities cause undesirable results. It is also necessary that the bobbin shall be readily doffed from and replaced upon the spindle with a minimum amount of exertion on the part of the operator because of the large number of spindles under the care of a single operator. It is also essential that the spindle shall be so constructed as not to become clogged with the fly and lint which collects upon the spinning frame and that the spindle shall be of sturdy construction to withstand not only the natural requirements of usage but the more or less rough treatment to which it is subjected in the doffing and replacement of the bobbin.

These and other considerations have led to the devotion of a great amount of inventive effort with the aim to improve and perfect the spindle.

The object of the present invention is to produce a spindle of this type which shall be of sturdy construction and in which the proper centering of the bobbin is readily and accurately secured under all conditions.

The further object of the invention is to provide a spindle construction of this type in which the clutch members fulcrum directly upon the spindle blade without any interposed spring or yielding feature.

The object of the invention is further to provide such a construction in which the

spring control of the clutch members is entirely exteriorly thereof and is so located as not to be subject to misplacement or injury.

These and other objects and features of the invention will appear more fully from the accompanying description and drawings and will be particularly pointed out in the claims.

As the general construction and operation of spinning and similar spindles with bobbin clutching members are well known and familiar to those skilled in the art, it will only be necessary here to illustrate and describe the parts directly concerned with preferred forms of the present invention.

In the drawings:

Fig. 1 is a side elevation partially broken away of a portion of a spindle embodying a preferred form of the invention.

Fig. 2 is a view similar to Fig. 1, but on a larger scale, and chiefly in vertical cross section.

Fig. 3 is a view in transverse cross section taken on the line 3—3 of Fig. 2.

Fig. 4 is a view similar to Fig. 2, but showing another form of the invention.

Fig. 5 is a view similar to Fig. 2 showing a further variation in the construction.

Fig. 6 is a side elevation of a sleeve and bobbin clutching segments illustrating a further variation in construction.

In the construction illustrated in Figs. 1, 2, and 3, the blade 1 of the spindle is generally of the usual form and has rigidly secured thereto, preferably by a driving fit, the whirl

2. In its upper face the whirl is formed with an annular recess 3 concentric with the blade. A cap 4, shown as formed of comparatively thin metal, presents an annular flat portion 5 extending over the top of the whirl concentric with the blade and forming a seat or rest for the bottom of the bobbin. The cap also presents a depending annular flange 6. The cap is tightly fitted to the upper end of the whirl, preferably by a driving fit between the flange 6 and the whirl.

The bobbin clutching feature of this invention comprises essentially, first, a plurality of similar rigid clutch members surrounding the blade, extending longitudinally thereof and fulcrumed between their ends directly

upon the blade so as to rock radially thereof; second, suitable means for limiting the outward movement of the upper ends of the clutch members; and, third, means, such as an annular contractile spring, located in the recess of the whirl acting upon the exterior of the clutch members yieldingly to press their lower ends toward the blade.

In the preferred construction illustrated, the clutch members are positioned circumferentially of the blade and the outward radial movement of the upper ends of the clutch members is limited and the structure is protected against collection of fly and lint by a sleeve of similar construction to that disclosed in the patent to Miller, No. 1,647,109, October 25, 1927. This sleeve 7 is a one-piece structure comprising a head portion 8 having an axial bore which fits the blade 1 with a driving fit. From the head portion 8 of the sleeve depends a plurality of similar symmetrically disposed circumferentially separated fingers 9 thus forming between the fingers a plurality of symmetrically disposed similar vertical slots which extend to the lower end of the sleeve. The side walls 10 of these fingers lie in planes parallel to the planes which extend radially midway the slots formed between the fingers. The exterior surface of the head 8 in the sections 11 which are directly above the slots between the fingers lies in or inside of the planes defined by the exterior edges 12 of the walls of adjacent fingers. This prevents any of the yarn in a mass of yarn accidentally wound on the bare spindle from catching as it is slid up over the bare sleeve. The sleeve is secured on the spindle preferably with a driving fit and with the lower ends of the fingers extending into the recess 3 of the whirl.

The bobbin clutching members, in the form illustrated, are severally mounted in the slots of the sleeve 7, are seated at their lower ends in the recess 3, and extend at their upper ends interiorly of the sleeve and are fulcrumed between their ends upon the blade so as to rock radially thereof in the sleeve slots. These clutch members 13 present exterior cylindrical surfaces adapted to fit the bobbin bore and the side walls of these clutching members fit snugly against the walls 12 of the fingers of the sleeve. At their upper ends the clutch members present lips 14 which lie in the interior of the head 8 of the sleeve and thus limit the outward movement of the clutch members. At their lower ends the clutch members may present out-turned feet 15. The fulcrum point 16 of these clutch members, it will be seen, is located between the ends of the clutch members and at this fulcrum point the clutch members engage the blade. Preferably, in this construction the radial thickness of each bobbin clutching member above the fulcrum 16 is substantially

as great as the limit of radial movement of the clutch member will permit. This renders each clutch member apparently heavy so that the centrifugal force exerted thereupon during the high speed of rotation of the spindle will act to increase the clutching action on the bobbin. The main feature relied upon for effecting the clutching action is a yielding means located in the recess 3 of the whirl exteriorly of the clutching members and acting to press their lower ends toward the blade. Such a yielding means is shown as an annular helical contractile spring 17 resting on the feet 15 and held from displacement by the flange 5 of the cap 4 of the whirl.

It will be seen that in this construction it is impossible for the clutch members to get out of position concentric with the blade because they fulcrum directly on the blade and there is no yielding element interposed between the clutch members and the blade.

The construction illustrated in Fig. 4 is similar to that described excepting that the clutch members 18 are shown of substantially uniform thickness and fulcrumed between their ends at 19 on a ferrule 20 having a sharp fulcrum edge 21 and rigidly secured to the blade 1 so as to form a functional part thereof. The contractile spring 22 is also shown as a split ring.

The construction shown in Fig. 5 is also similar to that shown in Figs. 1, 2 and 3, except that in this case the clutch members 23 have no outwardly projecting feet at the bottom as such feet are not essential in many cases, the sleeve acting to hold the clutch members in longitudinal position and the contractile spring 24 being positioned by the flange 25 of the whirl cap.

In the construction illustrated in Fig. 6, a further means is shown for maintaining the longitudinal position of the clutch members and insuring against their upward movement. In this case the sleeve 26 is constructed as already described, but the lower ends 27 of the sleeve segments or fingers 28 do not extend quite to the bottom of the recess in the whirl and the clutch members 29 are extended circumferentially at 30 beneath the lower ends of the sleeve segments so that the clutching members are thus prevented from having any undesirable upward movement.

In each of the forms thus described there is thus presented a spindle of great simplicity of construction, having no parts likely to get out of order, in which the clutch members fulcrum upon the spindle blade so as to insure their concentricity with the blade under all conditions, in which no yielding means is interposed between the blade and the clutch members, and in which the entire construction is rugged.

Having thus described the invention, what is claimed as new, and desired to be secured by Letters Patent, is:

1. A rotatable spindle comprising a blade, a whirl secured to the blade having an annular recess in its upper face concentric the blade, a sleeve concentric the blade and secured at its upper end thereto and having a plurality of symmetrically disposed similar vertical slots extending to the lower end thereof, a plurality of similar rigid clutch members mounted one in each sleeve slot, seated at their lower ends in said recess, extending at their upper ends interiorly of the sleeve and fulcrumed between their ends upon the blade to rock radially thereof in the sleeve slots, and means located in the said recess for yieldingly and exteriorly pressing the lower ends of the clutch members toward the blade.

2. A rotatable spindle comprising the construction defined in claim 1, in which the lower ends of the clutch members are extended circumferentially beneath the lower ends of the segments of the sleeve between the slots to prevent upward movement of the clutch members.

3. A rotatable spindle comprising a blade, a whirl secured to the blade having an annular recess in its upper face concentric the blade, a sleeve concentric the blade and secured at its upper end thereto and having a plurality of symmetrically disposed similar vertical slots extending to the lower end thereof, a plurality of similar rigid clutch members mounted one in each sleeve slot, seated at their lower ends in said recess, extending at their upper ends interiorly of the sleeve and fulcrumed between their ends upon the blade to rock radially thereof in the sleeve slots, and an annular contractile spring located in the said recess exteriorly of the clutch members and acting yieldingly to press the lower ends of the clutch members toward the blade.

4. A rotatable spindle comprising a blade, a whirl secured to the blade having an annular recess in its upper face concentric the blade, a sleeve concentric the blade and secured at its upper end thereto and having a plurality of symmetrically disposed similar vertical slots extending to the lower end thereof, a plurality of similar rigid clutch members mounted one in each sleeve slot, seated at their lower ends in said recess, extending at their upper ends interiorly of the sleeve and fulcrumed between their ends upon the blade to rock radially thereof in the sleeve slots, and an annular helical contractile spring located in the said recess exteriorly of the clutch members and acting yieldingly to press the lower ends of the clutch members toward the blade.

5. A rotatable spindle comprising a blade, a whirl secured to the blade having an annular recess in its upper face concentric the blade, a plurality of similar rigid clutch members extending longitudinally of the

blade, having their lower ends located in the said recess and fulcrumed between their ends upon the blade to rock radially thereof, means located in the said recess for yieldingly and exteriorly pressing the lower ends of the clutch members toward the blade, and means on the blade for limiting the radial outward movement of the upper ends of the clutch members.

6. A rotatable spindle comprising a blade, a whirl secured to the blade having an annular recess in its upper face concentric the blade, a plurality of similar rigid clutch members extending longitudinally of the blade, having their lower ends located in the said recess and fulcrumed between their ends upon the blade to rock radially thereof, an annular contractile spring located in the recess exteriorly of the lower ends of the clutch members and acting yieldingly to press them toward the blade, and means on the blade for limiting the radial outward movement of the upper ends of the clutch members.

7. A rotatable spindle comprising a blade, a whirl secured to the blade having an annular recess in its upper face concentric the blade, a sleeve concentric the blade and rotatable with the blade and whirl and having a plurality of symmetrically disposed vertical slots, a plurality of similar rigid clutch members mounted one in each sleeve slot, seated at their lower ends in the said whirl recess and in all positions fulcrumed between their ends upon the blade so as to rock in the sleeve slots radially of the blade upon their respective fulcrums, and means located in the whirl recess for yieldingly and exteriorly pressing the lower ends of the clutch members toward the blade.

8. A rotatable spindle comprising a blade, a whirl secured to the blade having an annular recess in its upper face concentric the blade, a plurality of similar rigid clutch members extending longitudinally of the blade, having their lower ends located in the said recess and fulcrumed between their ends upon the blade to rock radially thereof, means located in the said recess for yieldingly and exteriorly pressing the lower ends of the clutch members toward the blade, and means for limiting the radial rocking movement of the clutch members in the direction carrying the upper ends outward.

In testimony whereof, I have signed my name to this specification.

WALLACE I. STIMPSON.
